INTERNAL-COMBUSTION MOTOR AND
METHOD OF OPERATING IT

Lewis M. Showers, Lansdowne, Pa., assignor to
The Pennsylvania Railroad Company, Philadelphia, Pa., a corporation of Pennsylvania

Application March 11, 1943, Serial No. 478,744

6 Claims. (Cl. 123—179)

This invention relates to internal combustion motors. More especially, it is concerned with internal combustion motors of the spark-fired oil-consuming type, and with methods of operating such motors.

Motors of the kind specifically referred to are ordinarily designed to operate at a relatively low compression ratio, and are accordingly difficult to start when cold, since the amount of heat developed at that time by compression of the air in the cylinders is in itself insufficient to properly vaporize the injected fuel oil charges for the purposes of spark ignition.

Amongst the aims of my invention are to overcome the above drawback, i. e., to facilitate starting of spark-fired oil-consuming internal combustion motors; and to improve their performance generally. The attainment of these objectives in practice is made possible, as hereinafter more fully disclosed, through provision of means, whereby, at starting of the motors, a maximum quantity of air is permitted to enter the cylinders for operation at high compression, and whereby, as the motors heat up, the air supply is reduced for operation of the motors thereafter at lower compression; and through the further provision of automatic means sensitive to suction variations in the air inlets to the cylinders of the motors for proportionately controlling the amount of fuel injected into the cylinders during normal running.

Other objects and attendant advantages will appear from the following detailed description of the attached drawings, wherein Fig. 1 is a view in vertical section of an internal combustion motor conveniently embodying the present improvements.

Fig. 2 is a staggered fragmentary sectional view of the motor taken as indicated by the angled arrows II—II in Fig. 1.

Fig. 3 is a detail section taken as indicated by the angled arrows III—III in Fig. 2; and

Fig. 4 is a diagram showing the operating cycle of the motor.

The internal combustion motor herein illustrated for the exemplification of my invention is of the four cycle spark-ignition oil-consuming type having a single air-cooled cylinder 10 with a piston 11 therein connected, after common practice, by a pitman 12 to the crank or power shaft 13. Air admission, and exhaust into and from the cylinder 10 are controlled respectively by poppet valves 14 and 15 which seat against ports 16 and 17 in the cylinder head 18, said ports communicating respectively with coaxial

outwardly-extending inlet and outlet ducts 19 and 20 in said head. The valves 14 and 15 are biased individually by compression springs 21 and 22, being opened respectively by overhead 5 tappet levers whereof the one for the exhaust valve 15 is shown at 23 in Fig. 1 with its operating rod 24 extending down into the crank case 25 of the motor for actuation by a rise 26 on the cam shaft 27, which, as ordinarily, is driven from the crank shaft 13 by intermeshing spur gears conventionally indicated at 28 and 29. The spark for igniting the fuel charges is afforded by a spark plug 30, which, see Fig. 1, is screwed into an opening 31 in the cylinder head 18, timing of 10 the spark being controlled by suitable means (not shown) actuated from the crank shaft 13. At a point diametrically opposite the spark plug 30, the cylinder head 18 is provided with an axially bored boss 32 for connection of a fuel injecting 15 nozzle 33 which discharges by way of the lower flared portion 34 of the bore in said boss, into the top of the cylinder 10 above the piston 11. The nozzle 33 is of an approved adjustable type 20 designed to release under a definite regulatable pressure, and the fuel oil is delivered to it, by way of a connecting tube 35, from a reciprocating 25 pump 36 which receives oil by way of a pipe 37 from a suitable source of supply, not illustrated, and which has a plunger piston 38 actuated by another cam rise 39 on the cam shaft 27. The 30 pump 36 is of standard design having a rotary valve means (not shown) operable by a rack bar 41, see Fig. 1, in a well known manner.

For automatically controlling the pump valve 35 in accordance with my invention, I have provided a suction responsive device 42 whereof the cylinder 43 is connected by tubing 44 to the horizontal branch 45a of a special angular fitting 45 which forms a continuation of the intake duct 40 10 of the motor. The piston 47 of the suction responsive device 42 is subject to a spring 48 and coupled, by a link 49, with the rack bar 41 of the pump valve means. As shown, the vertical branch 45b of the fitting 45 is open at the top for attachment thereto of an air filtering device (not illustrated), and, as shown, formed with a by-pass 46c. Disposed in the branch 46b is a horizontal-axis auxiliary throttle 50, which, in accordance 45 with my invention, is automatically controlled by a bi-metal coil thermostat 51 lodged within a recess 52 in the cylinder head 18 of the motor, the interposed connections including an arm 53 on the shaft 54 of said throttle, an arm 55 on the shaft 56 of the thermostat, and a link 57 connecting said arms. As later explained, the 50 suction

iliary throttle 50 is closed during normal running of the motor. At starting, when the motor is cold, the auxiliary throttle 50 is open, the tail 53a of the lever 53 acting as a stop therefor in contact with the horizontal branch 45a of the fitting 45, as shown. Normally the air necessary for the operation of the motor is drawn in through a port 58 by way of which the horizontal branch 45a of the fitting 45 communicates with the by-pass 45c, flow through said port being governed by a poppet valve 59 which is responsive to suction against the pull of a compression spring 60 tending to keep it closed. As shown, the port 58 is located in the horizontal branch 45a of the fitting 45 intermediate the auxiliary throttle 50 and a main throttle 61 by which the speed of the motor is controlled, said main or control throttle being operable by means of a link rod 62.

In practice the cams on the cam shaft 27 are so arranged as to determine operation of the motor in accordance with the cycle diagrammatically represented in Fig. 4, wherein the rotation of the crank shaft is as indicated by the arcuate arrow at the left of the diagram. As indicated the air induction takes place during the whole of the suction stroke of the piston. During the succeeding up-stroke of the piston, the air is compressed, fuel injection starting approximately after the piston has reached the mid point of this stroke and the spark occurring shortly before full compression. From the diagram of Fig. 4 it will be further noted that the exhaust valve is opened slightly before the termination of the succeeding downward or power stroke of the piston, and remains open throughout the succeeding up-stroke of said piston.

As before stated, during normal running of the motor, the auxiliary throttle 50 is completely closed. Thus the air for combustion is normally drawn through the port 58 upon opening of the valve 59 by the suction created during the downward stroke of the piston during alternate rotations of the crank shaft, the speed of the motor being controlled in the usual way by the main throttle 61. The fuel supplied by the pump 36 for injection in the cylinder during each cycle is measured by shifting of the rod 41 under control of the cylinder 43, the piston 47 of which responds to variations in the suction attending air induction through the inlet 19. Also as hereinbefore intimated, the auxiliary throttle 50 is full open at cold starting of the motor so that a maximum amount of air is allowed to enter the cylinder through the inlet passage 45b. The large amount of air thus taken in is compressed to a high degree with incidental rise of its temperature to a point at which the fuel will be vaporized for firing by spark ignition. As the motor warms up the auxiliary throttle 50 is gradually moved to closed position as the thermostat 51 expands, whereafter the air will be drawn in through the port 58 as previously explained, and the motor operate at normal lower compression. During normal operation, the cylinder device 42 can be relied upon to apportion the fuel charges directly with suction variations in the air duct 18, as a consequence of which the maximum power will be developed by the motor with the most economic consumption of the fuel.

While I have for the purposes of exemplification herein described my invention in connection with a single cylinder motor of the four stroke cycle type, it is obvious that by suitable modifications within the scope of the appended claims, it can be readily embodied, with attainment of corresponding advantages, in multiple cylinder motors of either two or four stroke cycle.

Having thus described my invention, I claim:

- 5 1. In a spark-fired oil-consuming semi-Diesel internal combustion motor, a cylinder with a piston therein; a fuel injecting nozzle; an air inlet valve; an exhaust valve; an air duct with a throttle for controlling the speed of the motor; and means for admitting a maximum amount of air into the cylinder for operation of the motor at high compression at starting, and for automatically reducing the air supply as the motor warms up for normal running thereafter at lower compression.
- 10 2. In a spark fired oil consuming internal combustion motor, a cylinder with a piston therein; a fuel injecting nozzle; an air duct; a main or speed control throttle; an air inlet valve; an exhaust valve; an auxiliary throttle in the air duct ahead of the main throttle; a by-pass extending around the auxiliary throttle; a port intermediate the main and auxiliary throttles by way of which the air inlet and by-pass communicate; a suction responsive valve for admitting air into the inlet from the by-pass during normal running of the motor; and automatic actuating means whereby the auxiliary throttle is moved from full-open position for starting of the motor at high compression, to closed position when the motor is heated up for normal running of said motor thereafter at lower compression.
- 15 3. The invention according to claim 2, in which the automatic actuating means includes a thermostat within a hollow in a wall of the motor cylinder, and operating connections between the auxiliary throttle and said thermostat.
- 20 4. The invention according to claim 1, further including a pump for delivering the fuel under pressure to the nozzle, said pump having valve means for measuring the fuel charge delivered at each injection; and means sensitive to suction variation in the air inlet of the motor for actuating the fuel measuring valve means of the pump.
- 25 5. The method of operating spark-fired semi-Diesel oil-consuming internal combustion motors comprising admitting a large amount of air into the cylinders of the motors for starting at high compression; and reducing the air supply as the motors warm up for normal operation of the motors thereafter at lower compression.
- 30 6. The method of operating spark-fired semi-Diesel oil-consuming internal combustion motors comprising admitting a large amount of air into the cylinders for starting at high compression; reducing the air supply as the motors warm up for normal running of the motors thereafter at lower compression; and regulating the fuel charges injected into the cylinders of the motors proportionately with suction variations in the air inlets to the cylinders.

LEWIS M. SHOWERS.
